ATTORNEYS.

UNITED STATES PATENT OFFICE.

ALADAR HOLLANDER, OF BERKELEY, CALIFORNIA.

DEEP-WELL PUMP HEAD.

Application filed March 27, 1924. Serial No. 702,239.

To all whom it may concern:

Be it known that I, ALADAR HOLLANDER, a citizen of the United States, and resident of the city of Berkeley, county of Alameda, State of California, have invented new and useful Improvements in Deep-Well Pump Heads, of which the following is a specification.

My invention consists in structural improvements in the head of a deep well pump, whereby the bearing by which the weight of the rotating elements of the pump are supported is cooled by the water discharged from the pump, and wherein means is introduced to prevent water gaining access within the bearing and pump head, thus enabling proper lubrication and operating conditions to be secured and most efficient operation maintained at all times.

Other objects will appear from the drawings and specifications which follow.

It is customary to construct vertical shaft deep well pumps with a column through which the water discharges, and through substantially the center of which column an operating shaft extends from the top to approximately the bottom of the well. The operating shaft is sometimes enclosed in an inner tube to prevent access of water to the rotating shaft and to support the bearings for the shaft, and to thus provide a lubricating means to the bearings and shaft. The lubricant being furnished through or into the inner tube and thus into the bearings while the water discharging from the pump impeller at the bottom of the well passes freely through the passage formed between the column and the inner tube. In other cases the inner tube is omitted and the vertical shaft is carried through water lubricated bearings; or other bearings and lubricating devices may be employed to suit individual requirements.

The weight of the vertical rotating element and any other axial thrusts are carried by bearings usually mounted at the top of the well or in the head, as it is generally called in the art. The shaft being driven either by pulley and belt or gearing, or in the most improved practice, by direct connected electric motor. In all of such cases the bearing carrying the weight and thrust in the head must be kept free from water, although water under the discharging pressure is in contact with the shaft up to the head chamber in cases where an inner tube

is not used, and is in close contact with the inner tube up to the head where the inner tube is used. In both cases water leakage into the head readily injures the bearings or electrical connections or both.

My invention prevents this.

By referring to the accompanying drawings and specifications my invention will be made clear.

Fig. 1 is a cross section through the head of a deep well pump having an exposed driving shaft, and to which my invention has been applied.

Fig. 2 is a detailed showing of the type of gland and drain pocket of Fig. 1, showing my invention applied to a similar pump but where an inner tube is employed around the shaft.

Throughout the figures similar numerals refer to identical parts.

A conventional pump column is shown by the numeral 1. A driving shaft is shown at 2 and a conventional impeller of any type not shown but well known is to be understood as mounted on the lower extended portion of the shaft 2. Water is discharged in the direction of the arrow 3 through the pump head outlet 4. At 5 is a casing enclosing an electric motor having a stator 6 and rotor 7. The rotor is keyed at 8 to the sleeve 9 which latter is provided with a thrust bearing at 11 to carry the weight. This latter bearing is mounted in intimate relation with the wall 12 on the lower side of which the discharging water freely flows, thus removing any heat generated in the bearing at all times during the operation.

The shaft 2 with its fixed parts and having considerable weight is fixed in driving relation to the sleeve 9 by the key 13 and supported in axial adjustment by the threaded nut at 14. At 16 is a gland, the lower side of which is exposed to the flowing water 3 and preferably having a packing ring at 17 and through which gland the shaft 2 rotates with close clearance. At 18 is an annular pocket drained through the passageway 19 to the outside of the pump column and at 20 is a bushing around the shaft having a running fit in the machined portions of the head. It will now be seen that any leakage of the pressure water 3 between the gland 16 and the shaft 2 in the direction of the arrow 21 will be trapped in the pocket 18 and drained through the passageway 19 and discharged as indicated by the arrow

22, external to the pump head and thereby preventing any water from getting into the interior 23 of the motor and bearing shell or housing 5. The motor is energized by 5 the leads 24, 25 passing through the inverted conduit 26. The motor and casing and sleeve features and their connecting parts as above described form the subject of a separate application and are not claimed 10 herein.

Where an inner tube is employed inclosing the shaft 31 as shown at 30, I carry the said inner tube through the gland 32 and to above the pocket 34 and into the rigid portions 15 of the head while providing a pocket 34, and at 35 a detector passage similar to 18, 19 whereby any water leakage which may find its way between the gland 32 and tube 30 from the pump discharge as shown by the 20 arrow 36 is trapped in the pocket 34 and drained through the passage 35 as before.

The discharging water cools the bearings within the casing by its contact and consequent removal of heat, from the surfaces of the casing as at 37. 25

I claim:

In a head for deep well vertical shaft pumps having an inner tube extending therefrom and enclosing said shaft, a discharge throat, a bearing for said shaft in metallic 30 contact with said throat, gland means around said inner tube and within said throat to prevent leakage into said bearing, a pocket outside the inner tube between the said gland means and the said bearing and a discharge passage from the said pocket to the exterior of the head, said inner tube telescoping with the stationary parts of said head between the pocket and the bearing substantially as and for the purpose set 35 forth. 40

ALADAR HOLLANDER.
